ELECTRIC IRON PLUG AND RECEPTACLE
THEREFOR

John P. Walpole, Bronx, N. Y.

Application February 18, 1938, Serial No. 191,320

1 Claim. (Cl. 177—311)

This invention relates to improvements in electrical connectors to be used in conjunction with portable devices and more particularly to an improved electrical connector unit and receptacle for use in conjunction therewith especially adapted for use with electric irons and the like.

Heretofore, in electric irons and similar devices, current has been supplied to the portable unit by means including a length of flexible electrically conductive cable connected to said unit by means of a connector plug upwardly projecting from the handle portion thereof. This type of structure is characterized by several disadvantages, notably, the cable, though flexible, interferes with the work of the user by getting in the path of the moving iron, by entangling with itself, with the work being ironed, etc. Further, the continuous flexing of the cable through movement of the iron causes breaks therein which in some instances can result in a fire hazard due to arcing. Breaks are especially likely to occur at the junction between cable and plug, inasmuch as during the use of an iron it is often necessary for the user to disconnect the power source from the iron, which is usually done by pulling the plug out.

Among the other disadvantages with electrical units of the type referred to can be included that no means are provided for indicating whether 30 or not a device is connected to a power source whereby burning out of the resistance element in the iron often occurs through inadvertent failure to disconnect the unit from the power source when not in use.

It is among the objects of the present invention to provide a new and improved connector plug adapted to be used with at least most types of irons as now made which, functioning in conjunction with a new and improved receptacle, 40 serves to provide means for supplying power to an electric iron when the latter is positioned adjacent the receptacle but not at other times and, further, provides means for visibly indicating when the electric iron is connected to the power source. It will be observed that in this manner the use of a plug in a connector cable directly connected to the iron and moving therewith, is obviated, thereby avoiding the difficulties hereinabove referred to of devices heretofore known.

It is also an object of the present invention to provide a new and improved type of connector plug and receptacle therefor, wherein arcing 55 between the plug contacts and the receptacle of

electrical contact is made, will be at least in a large measure minimized.

Notable among the features of the device according to the present invention are that it provides a visibly displaying means for indicating 5 electrical connection between the power source and the iron; that the iron during use is normally dissociated from the power source; that the novel plug and adapter receptacle according to the present invention can be used in conjunction with at least most types of irons now 10 in use; that current-carrying terminals are concealed within insulative structures, whereby accidental short-circuiting of the line by the user or shocking of the user is at least minimized; and that the novel plug receptacle according to 15 the present invention is formed of relatively few parts which are easily fabricated and assembled whereby concomitant economies in production and maintenance can be effected.

Other objects, advantages and features of the device according to the present invention will be apparent to those skilled in the art during the course of the following description wherein a specific embodiment of the present invention, 25 herein illustrated, will be described, it being clearly understood however, that the illustrated preferred embodiment is given solely by way of example and is non-limitative.

In the drawing:

Fig. 1 is a side elevational view of the preferred embodiment of the present invention showing the plug and adapter receptacle arranged for use in conjunction with a saddle iron and stand therefor;

Fig. 2 is an exploded perspective view of the connector plug according to the present invention;

Fig. 3 is substantially a vertical sectional view of the device illustrated in Fig. 2, taken along 40 the line 3—3, portions of the saddle iron being shown in phantom;

Fig. 4 is substantially a vertical sectional view of Fig. 1 taken along the line 4—4;

Fig. 5 is substantially a vertical sectional view 45 of Fig. 4 taken along the line 5—5, and

Fig. 6 is substantially a schematic wiring diagram showing interconnection of the iron and parts of the iron rest.

Regarded in certain of its broader aspects the 50 present invention comprises a novel combination of plug and adapter receptacle therefor. The plug comprises a member adapted to engage with, and be carried by, the projecting connector terminals of an iron or similar device and arranged, 55

when so carried, to present a pair of horizontally disposed projecting plug terminals electrically connected to the terminals of said iron. The adapter receptacle comprises means for receiving 5 said horizontally disposed projecting connector members of said plug and means connected with the power supply whereby under certain conditions current delivered from said power supply can be transmitted to said means associated with 10 said plug, and means for visibly indicating when said electrical connection between power source and plug terminals is made.

In order to facilitate a fuller and clearer understanding of the matter of the present invention, a specific illustrated preferred embodiment 15 thereof will be hereinafter described, corresponding reference characters being used throughout the several figures to designate equivalent or the same parts.

20 A saddle iron of typical design is generally designated by the numeral 10 and comprises a handle portion, part of which is designated at 11, and connector plug supporting means comprising the parts generally indicated at 12 and 25 13, the latter serving, in conjunction with the member 11, to support the handle hereinbefore referred to. The members 12 and 13 jointly serve as supporting means for the connector plug generally designated at 14 which, in a manner 30 hereinafter to be described, engages and cooperates with adapter receptacle portions generally indicated at 15 of the base or stand member 16.

Referring now to Figs. 2 and 3 wherein the 35 details of the novel plug according to the present invention are best illustrated, it will be observed that the plug proper comprises an obliquely disposed portion 20, adapted to engage with terminals of the iron, and supporting means generally designated at 21 presenting a pair of projecting horizontally positioned terminals 22 and 23. The portion 20 containing the terminals adapted to engage with terminals carried on the electric iron, comprises an electrically insulative shell or container part 25 carrying a pair of terminal receptacles, one of which is designated at 26, adapted to receive and electrically contact terminals, one of which is designated at 27, of the electric iron 10. The members 26 are 50 held electrically insulated from each other within the electrically insulative block 25 and are adapted to engage with terminals and are arranged in spaced relationship with respect to each other to correspond with the uniform and 55 standard spacing between terminals on electric irons, thereby permitting use of the plug in conjunction with standard equipment. The upper portion of the electrically insulated block is formed to present a pair of extending arm-like members 29 and 30, substantially as shown in Fig. 2, the free ends of said arms 29 and 30 being united to provide the terminal supporting portion generally designated at 21. It will be observed that an opening 31 is defined by the 60 arms 29 and 30, said opening being provided to permit use of the plug with certain types of irons having upwardly projecting plug supporting members 12, said member 12 being adapted to pass through said opening 31 whereby the plug 65 when positioned upon the iron presents substantially the appearance shown in Fig. 1. Electrically conductive members, one of which is designated at 35, pass through the internal portions of the arms 29 and 30 and serve to connect the horizontally positioned projecting plug

elements 22 and 23 with the terminals of the iron. In order to provide a more rugged construction of the plug generally designated at 14, it is preferred that supporting members 40 and 41 be provided, being formed as indicated at 40a 5 and 41a respectively, to conform with the outline of the portion 20 of the member 14 and being formed at portions 40b and 41b to conform with portion 21 of said member and held in position by means including a screw 42 and wing nut 43. 10 It will be apparent when the plug is positioned upon an iron in the manner indicated in Fig. 1, that the horizontally positioned projecting terminals 22 and 23 will be electrically connected to the terminals of the iron proper and, accordingly, when electrical power is supplied to said terminals 22 and 23, said iron will function. 15

Referring now to Figs. 4 and 5 wherein the adapter receptacle 15 is best illustrated, it will be noted that it comprises a substantially hemi-cylindrical casing member 50 closed at one end by a wall 51 and having an opening formed in the other wall 52 alignable with the plug element-carrying portion 21 of the plug 14 when the iron used in conjunction with said plug is positioned 20 on the base plate 53 and the stand generally indicated at 16. A receptacle 54 is provided in one side of the casing 50 and is adapted to receive a connector plug of conventional type, terminals generally indicated at 55 being provided within 30 said receptacle and adapted to engage with said plug in substantially the usual manner. Said terminals 55 are mounted in a block 56 formed of electrically insulative material which is supported within the hollow casing member 50 substantially as shown. Another portion of the block 56 is hollowed out to form a chamber 57 having openings formed in the upper portion thereof alignable with pins 22 and 23 when said plug 14 is carried upon an iron in the manner 40 hereinbefore described. Movable contact members 60 and 61, pivoted within the chamber 57 by means including pins 58 engaging with openings in portions of the block 56 and with openings in a partition 62 therein, are positioned adjacent 45 the openings formed in the upper portion of the chamber 57 hereinbefore alluded to. The upper parts of said members 60 and 61, indicated at 60a and 61a respectively, are flared to present lip-like members adapted to receive the projecting 50 plug portions 22 and 23 of the plug 14 when positioned substantially as shown in Fig. 1. Lower portions of said members 60b and 61b, respectively, of the members 60 and 61 are flared to receive and engage with terminals one of which is 55 designated at 63 positioned adjacent thereto substantially as shown in Fig. 5, said terminals being associated by electrically conductive members with the terminals 55 connected to the power source. 60

It will be noted that when terminals 22 and 23 are engaged with portions 60a and 61a of the members 60 and 61 respectively, and when the portions 60b and 61b of said members engage with the terminals, one of which is indicated at 63, the electric iron connected with plug 14 is placed in electrical circuit with the power source. The members 60 and 61 are normally dissociated from the terminals, one of which is designated at 63, by means including a spring-tensioning 70 member 64 connected to a portion of the electrically insulative block 56 and connected to a cross-piece 65 held in portions of the members 60 and 61, whereby said tensioning means 64 normally tends to impart counter-clockwise rotative move- 75

ment to the members 60 and 61 when the parts are positioned substantially as shown. Thus, it will be seen, although the power source is connected at all times to the terminals, one of which is designated at 63, that it is necessary to impart rotative movement to the members 60 and 61 as, for example, by pressing the projecting horizontally positioned members 22 and 23 into the portions 60a and 61a thereof in order to complete the circuit between power source and the device associated with the plug 14.

As hereinbefore mentioned, means are provided in accordance with the present invention for visibly displaying and indicating electrical connection between power source and iron. This means comprises a lamp 70 mounted in a socket 71 and connected by means of electrically conductive members 72 and 73 to terminals 74 and 75, respectively, mounted in a portion of the block 58 and disposed within the chamber 57 adjacent but behind the members 60 and 61, whereby as said members 60 and 61 are rotated the back portions thereof abut against and form electrical contacts with said members 74 and 75 thereby placing said lamp 70 in parallel electrical circuit. Accordingly, it will be noted that when an iron 10 provided with a plug 14 associated in the manner illustrated in Fig. 1, is positioned with projecting terminals 22 and 23 engaged with portions 60a and 61a of the members 60 and 61 that the lamp 70 placed in parallel electrical circuit including the said electric iron will indicate completion of the circuit between the power source and said electric iron. It will be noted when the terminals 22 and 23 of the connector plug 14 are not engaged as aforesaid with the portions 60a and 61a of the members 60 and 61, that said members will be moved out of contact with the terminals 74 and 75 by means including the spring-tensioning means 64 and the crosspiece 65, thereby dissociating the lamp 70 from the electrical circuit with the power source and visibly indicating dissociation of the said iron 10 from the power source.

In the preferred embodiment of the present invention an opening is provided in the casing 58 adjacent the lamp 70 wherein is mounted a

colored translucent or transparent port 80, whereby light from said lamp passes through said port to visibly indicate connection between power source and device to the user as aforesaid.

The electrical interconnection of the elements of the iron rest and the iron will be obvious from consideration of Fig. 6 wherein for convenience the above described parts of the device are designated by corresponding reference characters.

It is to be understood that this improvement is capable of extended application and is not confined to the exact showing of the drawing nor to the precise construction described and, therefore, such changes and modifications may be made therein as do not affect the spirit of the invention nor exceed the scope thereof as expressed in the appended claim.

What is claimed is:

An iron rest connected to a source of electric power cooperating with horizontally projecting terminal lugs of the iron plug to permit transfer of electric power to said iron which comprises a standard having openings formed therein registerable with and adapted to receive said horizontally positioned projecting lugs, a pair of terminal plates mounted within said standard adjacent said openings and connected to a source of electric power, a pair of pivoted electrically conductive arms positioned adjacent said openings adapted to engage with and be moved by said lugs when pushed through said openings engaging with said terminal plates whereby electric power can be conducted from said source to said device, said arms when dissociated from said lugs being moved by means including a spring-pressed yoke out of contact with said terminal plates, and means for visibly indicating completion of electrical circuit including power source and device, which comprises a pilot lamp and contact forming members electrically connected to said lamp, said members being engageable with said pivoted arms when moved into contact with said terminal plates whereby said pilot lamp is electrically connected into said circuit and energized thereby.

JOHN P. WALPOLE.
